ARTHUR DEBENHAM AND DANIEL GONTA, OF LENNEY, SASKATCHEWAN, CANADA.

TIE PLATE.

Application filed April 24, 1928. Serial No. 272,522.

This invention relates to rail fastenings, and embodies an improved tie-plate and spike for attaching a rail to a tie.

The object of the invention is to provide an improved anti-creeping plate and fastening, which will prevent movement of the plate with respect to the tie and also prevent movement of the rail with respect to the plate.

10 A further object of the invention is to provide an improved tie plate having the advantages referred to and which may be produced at a relatively low cost.

These and other objects are effected by 15 providing a plate having a lip which overlaps one edge of the rail base, and by providing a wedge shaped lock engaging the other edge of the rail base, fastened by a spike which when driven through the plate and into 20 the tie will hold the lock which presses against the opposite edge of the rail base and so forces the base tightly against the lip whereby creeping is prevented; and no special rail structure is necessary.

25 One form of the invention is illustrated in the accompanying drawings in which Fig. 1 is a perspective view of the device in use. Fig. 2 is a top plan of the tie plate and rail base. Fig. 3 is a section on the line 3—3 of Fig. 2.

In the drawings, the rail is indicated at 6, of the usual form. The tie-plate is indicated at 7 and its top surface is preferably tilted at a slight angle where the rail seats upon it. 30 The bottom of the plate has a series of cross ribs 8 with intervening depressions 9, the ribs being raised from the bottom face of the plate so as to bite into the tie and prevent the plate shifting.

35 At the side of the tie-plate opposite the lip an abutment 13 is provided, projecting upwardly from the surface of the plate, and preferably cast integral therewith. The inner face of this abutment or lug, that is the 40 face 14 next to the rail base, is at an angle to

the line of the rail, and has at the top a lip 15 projecting inwardly. A wedge 16 is driven between this abutment and the edge of the rail base, and this wedge has on its inner side a groove 17 in which the edge of the rail base is engaged. The top face of the plate is stepped down or recessed slightly, as indicated at 18, to permit the inner edge of the wedge to engage under the edge of the rail base. The smaller end of the wedge is formed 55 with an offset or shoulder 19, and after the wedge is driven in a spike 20 is driven behind this shoulder, through a prepared spike hole in the plate, and so locks the wedge in place against accidental removal. The spike 60 must first be removed before the wedge can be driven out. The ordinary spike may be driven through the spike hole 21.

The wedge by its action jams the rail base 65 against the lip 10 and locks it against creeping and so binds the rail and tie-plate together as to form a rigid fastening which cannot become loose under any ordinary conditions. The lateral thrust against the rail base, due to the wedge, is superior in its holding effect 70 to the action of ordinary spikes which often become loose in the tie and exert no such binding pressure as that described above.

We claim:

The combination of a tie-plate having a lip 75 thereon adapted to overlap one edge of a rail base, and having an upstanding abutment opposite the lip, a wedge fitting between said abutment and the opposite edge of the rail base and adapted to clamp the said base 80 against said lip, the small end of the wedge projecting beyond said abutment and having a shoulder, and a spike driven through the plate, between and in contact with said shoulder and the abutment, to prevent withdrawal 85 of the wedge.

In testimony whereof, we affix our signatures.

ARTHUR DEBENHAM.
DANIEL GONTA.
